EXTENSION CLAMP FOR AUTOMOBILE BODY AND FRAME REPAIR SYSTEM

Wayne E. Hunnicutt, Big Bend, and Peter G. Rossbach,
Waukesha, Wis., assignors to Applied Power Industries, Inc., Milwaukee, Wis., a corporation of Wisconsin

Filed July 15, 1968, Ser. No. 12,751

Term of patent 14 years

Int. Cl. D12—99

U.S. Cl. D41—1

Fig. 1

Fig. 2

Fig. 3

Fig. 4

Fig. 5

FIG. 1 is a top plan view of the extension clamp for automobile body and frame repair system showing our new design;

FIG. 2 is a bottom view thereof;

FIG. 3 is a side elevational view thereof, the two side views being essentially identical;

FIG. 4 is a front or clamp end view thereof; and

FIG. 5 is a rear elevational view thereof.

We claim:

The ornamental design for an extension clamp for automobile body and frame repair system, as shown and described.
